UNITED STATES PATENT OFFICE.

RALPH A. SQUIER, OF TIETON, WASHINGTON.

TOOL.

Application filed March 8, 1924. Serial No. 697,781.

To all whom it may concern:

Be it known that I, RALPH A. SQUIER, a citizen of the United States, residing at Tieton, in the county of Yakima and State 5 of Washington, have invented certain new and useful Improvements in Tools; and I do hereby declare the following to be a full, clear, and exact description of the invention, such as will enable others skilled 10 in the art to which it appertains to make and use the same.

The present invention relates to tools, and more particularly to that class of such devices as are used for driving in nails and 15 the like.

An object of the present invention is to provide a hatchet or hammer used particularly in making wooden boxes and which is provided with an impact surface of such 20 construction as to prevent the slipping of the hatchet or hammer on the heads of the nails in withdrawing the nails from the stripper or feeder which is used where wooden boxes are made in large quantities.

25 Another feature of the invention is to provide the head of the tool with an impact surface composed of a multiplicity of teeth which have their axes inclined to the base of the teeth, so that by impact of the head 30 of the tool against the nails as they come from the nail stripper the nails are driven in by a direct impact in line with the nails even though the tool must be struck by a glancing blow against the heads of the nails.

35 A further object of the invention is to provide the head of the tool with an impact surface which is stepped or composed of a plurality of inclined surfaces which are adapted to divert glancing blows into direct 40 longitudinal impact against the heads of the nails, so as to drive the nails in a straight line and prevent them from assuming an inclined position or from springing out of position when struck.

45 Another object of the invention is to provide a nail driving tool with a head whose impact surface is composed of a multiplicity of relatively small independent and inclined surfaces approximately of the size of the head of the nail so as to fit against the heads of nails and divert glancing blows into longitudinal thrusts against the heads 50 of the nails.

55 With the foregoing and other objects in view, the invention will be more fully described hereinafter, and will be more par-

ticularly pointed out in the claim appended hereto.

In the drawings, wherein like symbols refer to like or corresponding parts throughout the several views,

Figure 1 is a perspective view of a nail driving tool constructed according to the present invention, the same in the present instance being embodied in the form of a 65 stripping hatchet.

Figure 2 is an outer edge view of the tool of Figure 1, showing the inclined teeth on the impact surface of the head.

Figure 3 is a side elevation of the same, 70 and

Figure 4 is an enlarged face view of the impact head, showing the arrangement of the inclined teeth.

Referring to the drawing the present invention is embodied in a stripping hatchet having a blade portion 10, an intermediate socket portion 11 in which is suitably secured a handle 12, and a head or striking portion 13 which is arranged oppositely to 75 the blade 10.

The head 13 preferably has a slightly convexed striking face 14 which is made up of a plurality of relatively small projections or teeth 15 of substantially pyramidal form, 85 but whose axes are inclined relatively to the surface 14 and provide a number of independent inclined striking faces 16 adapted to directly engage the heads of nails so as to divert glancing blows of the head 13 into longitudinal thrusts against the head of the nail. 90

As shown in Figures 2 and 4 the teeth 15 may be all inclined in one direction, such as to the left as shown in Figure 4 so that glancing blows of the tool against nails which are held in the stripper will cause the inclined faces 16 to engage the heads of the nails and divert the same directly downward for freeing the nails from the stripper and for initially placing the nails in the work. 100 As it is necessary to continuously use the tool without interruption the tool may be continuously struck against the nails as the work is drawn away from the stripper and may then be brought into engagement with the next succeeding nail so as to free it from the stripper and initially place it in the work. Necessarily during such manipulation of the tool the same is impacted by a glancing blow against the head of the nail 110 in the stripper and also against the nail as

the work is drawn from beneath the chute or guide of the stripper and the inclined faces 16 thus permit of this practice in the natural use of the tool and at the same time 5 insure the correct driving in of the nails. Of course the inclination of the sides or faces 16 of the teeth may be varied or disposed at different angles and in different directions to meet various conditions of use 10 which may be found more advantageous for different classes of work and for different kinds of stripping machines.

The particular structure which is disclosed in the accompanying drawing is for 15 use by a right hand worker, but of course the teeth 15 may be inclined in an opposite direction for a left hand worker or to meet other requirements.

It is obvious that various changes and 20 modifications may be made in the details of construction and design of the above specifically described embodiment of this inven-

tion without departing from the spirit thereof, such changes and modifications being restricted only by the scope of the following claim.

What is claimed is:—

A nail driving tool for use in connection with nail stripping machines, comprising a body portion having a head with an impact surface composed of a plurality of independent teeth, each tooth having a flat face on one side extending outwardly at substantially right angles to the impact surface and having an inclined contact face at its opposite side, said flat faces of all of the teeth facing in one direction toward said nail stripping machine and all of said inclined contact faces extending away from said machine for impact with the heads of nails to deflect glancing blows thereon of the tool into an impact force coaxial with the nails to drive the same straight into the work.

RALPH A. SQUIER.
